UNITED STATES PATENT OFFICE

163,437

METALLOGRAPHIC MICROSCOPE

John T. Armbruster, Niagara Falls, and Leslie J. Peters, Buffalo, N. Y., assignors to American Optical Company, Southbridge, Mass., a voluntary association of Massachusetts

Application December 21, 1950, Serial No. 13,532

Term of patent 14 years

(Cl. D57—1)

To all whom it may concern:

Be it known that we, John T. Armbruster and Leslie J. Peters, citizens of the United States of America, residing at Niagara Falls and Buffalo, respectively, in the counties of Niagara and Erie, respectively, and State of New York, have invented a new, original, and ornamental Design for Metallographic Microscope, of which the following is a specification, reference being made to the accompanying drawings, forming a part thereof.

In the drawing:

Fig. 1 is a side front perspective view of a metallographic microscope showing the new design;

Fig. 2 is an opposite side front perspective view thereof;

Fig. 3 is a side elevational view; and

Fig. 4 is a front elevational view thereof.

The characteristic features of the new design reside in the portions shown in full lines in the drawing.

We claim:

The ornamental design for a metallographic microscope, substantially as shown and described.

JOHN T. ARMBRUSTER.
LESLIE J. PETERS.
